TREATING HYDROCARBON FLUIDS

Francis Owen Rice, Silver Spring, Md., and Winston D. Walters, Rochester, N. Y., assignors, by mesne assignments, to Process Management Company, Inc., Wilmington, Del., a corporation of Delaware

No Drawing. Application October 25, 1940,
Serial No. 362,871

9 Claims. (Cl. 260—683)

This invention relates to the treatment of hydrocarbon fluids.

According to our invention, higher molecular weight hydrocarbons are converted to lower molecular weight hydrocarbons. Thermal processes for effecting this conversion are known but we have found that by using a relatively small amount of a promoter, the rate of conversion is increased and the conversion may be carried out at lower temperatures. In our process the promoter which is used is diacetyl. Our invention may be used for the conversion of normally gaseous hydrocarbons to unsaturated hydrocarbons and for the conversion of mixtures of hydrocarbons containing normally gaseous paraffin hydrocarbons.

The proportion of the diacetyl used as a promoter may vary between about .045% by volume to about 1.5% by volume of the hydrocarbon to be converted. The conversion varies with the amount of promoter, being greater for larger percentages of promoter. The rate of conversion increases with increases in the temperature and pressure, and with higher temperatures and pressures shorter times of contact may be used. The highest temperatures for the conversions of saturated hydrocarbons promoted with diacetyl are encountered in the promoted conversions of ethane. The catalytic effect of the diacetyl decreases gradually with time.

The normally gaseous paraffin hydrocarbons such as ethane, propane and butane require high temperatures for decomposition when no catalyst or promoter is used and at such high temperatures the reaction is difficult to control. We have found that if the conversion is carried out in the presence of a relatively small amount of diacetyl, the reaction takes place at a lower temperature to give increased yields and at such a lower temperature the conversion is more easily controlled.

For example, butane was heated under a pressure of about $\frac{1}{2}$ an atmosphere to about 990° F. in the presence of about 1.0% of diacetyl by volume. After about five minutes under these conditions, about 32% of the butane was decomposed and the conversion products contained unsaturated hydrocarbons including butylene and ethylene. The unsaturated hydrocarbons may be separated in any suitable manner and further treated as desired. In all the examples using diacetyl as a promoter it is necessary to have the saturated hydrocarbon at a temperature such that the paraffin hydrocarbon would be itself decomposing at a measurable rate, if no promoter were

present. The diacetyl acts as a promoter to increase the rate of conversion. Pressures higher than those given in the examples may be used.

In another example, butane was decomposed under the conditions given in the preceding example except that only about 0.12% of diacetyl by volume was used. About 24% of the butane was decomposed and the reaction products contained unsaturated hydrocarbons.

At lower temperatures the rate of decomposition of the butane is decreased. For example, with about .10% of diacetyl by volume and at a temperature of about 954° F., about 13% of the butane was decomposed after about five minutes and the reaction products contained unsaturated hydrocarbons.

To convert propane into unsaturated hydrocarbons, about 1.0% of diacetyl by volume was added to propane and the mixture was heated to about 930° F. and under a pressure of about atmospheric. About 5% of the propane was decomposed and the reaction products contained propylene and ethylene. The propane was maintained under these conditions for about 15-20 seconds.

By heating the propane in the presence of about 1.0% diacetyl by volume to about 1112° F., about 20% of the propane was decomposed and the reaction products contained unsaturated hydrocarbons. Increasing the temperature to about 1157° F. and with the rest of the conditions the same, about 35% of the propane was decomposed in the presence of 1.0% diacetyl. The reaction products contained unsaturated hydrocarbons.

In all of the above examples, the converted products may be treated to separate unsaturated hydrocarbons and the unconverted paraffin hydrocarbons may be recycled for further treatment in the presence of added diacetyl.

While we have given several examples of our invention, these are merely for the purpose of illustration and we are not to be restricted thereto as the proportions of the promotor, the temperatures and pressures and times of heating may be varied without departing from the spirit of our invention.

We claim:

1. A method of converting normally gaseous paraffin hydrocarbons to unsaturated hydrocarbons which comprises heating a normally gaseous paraffin hydrocarbon to a conversion temperature in the presence of a relatively small amount of diacetyl to convert the normally gaseous paraffin hydrocarbon to unsaturated hydrocarbons.

2. A method of converting normally gaseous

paraffin hydrocarbons to unsaturated hydrocarbons which comprises heating a normally gaseous paraffin hydrocarbon to a conversion temperature in the presence of between about .045% and 1.5% by volume of diacetyl to convert the normally gaseous paraffin hydrocarbon to unsaturated hydrocarbons.

3. A method of converting normally gaseous paraffin hydrocarbons to unsaturated hydrocarbons which comprises heating a normally gaseous paraffin hydrocarbon to a temperature between about 930° F. and 1157° F. in the presence of a relatively small amount of diacetyl.

4. A method of converting normally gaseous paraffin hydrocarbons to unsaturated hydrocarbons which comprises heating propane to a conversion temperature in the presence of a promoter comprising diacetyl.

5. A method of converting normally gaseous paraffin hydrocarbons to unsaturated hydrocarbons which comprises heating propane to a conversion temperature in the presence of about 1.0% of diacetyl by volume.

6. A method of converting normally gaseous paraffin hydrocarbons to unsaturated hydrocarbons which comprises heating propane to about 930° F. to 1157° F. in the presence of about 1.0% of diacetyl by volume.

7. A method of converting higher molecular weight hydrocarbons to lower molecular weight hydrocarbons which comprises heating hydrocarbons between about 930° F. and 1157° F. in the presence of a relatively small amount of diacetyl.

8. A method of converting normally gaseous paraffin hydrocarbons to unsaturated hydrocarbons which comprises heating butane to a conversion temperature in the presence of about 1% of diacetyl by volume.

9. A method of converting higher molecular weight hydrocarbons to lower molecular weight hydrocarbons which comprises heating hydrocarbons to a conversion temperature in the presence of a relatively small amount of diacetyl.
